(57) CLAIM

The ornamental design for a stamp, as shown and described.

DESCRIPTION

FIG. 1 is a front elevation of a stamp showing our new design;

FIG. 2 is a rear elevation thereof;

FIG. 3 is a right side elevation thereof;

FIG. 4 is a left side elevation thereof;

FIG. 5 is a top plan elevation thereof;

FIG. 6 is a bottom plan view thereof;

FIG. 7 is a cross-sectional view taken along line A—A in FIG. 1;

FIG. 8 is a cross-sectional view taken along line B—B in FIG. 3;

FIG. 9 is a front elevation of the stamp body with the cap omitted for ease of illustration;

FIG. 10 is a rear elevation thereof;

FIG. 11 is a right side elevation thereof;

FIG. 12 is a left side elevation thereof;

FIG. 13 is a top plan view thereof;

FIG. 14 is a bottom plan view thereof;

FIG. 15 is a front elevation of the cap member with the stamp body omitted for ease of illustration;

FIG. 16 is a rear elevation thereof;

FIG. 17 is a right side elevation thereof;

FIG. 18 is a left side elevation thereof;

FIG. 19 is a top plan view thereof; and,

FIG. 20 is a bottom plan view thereof.
